STARTING SIGNAL FOR ROAD RACE SETS

Ronald K. Ford, Orange, Calif., assignor to Eldon Industries, Inc., Hawthorne, Calif., a corporation of California

Filed May 3, 1965, Ser. No. 85,076

Term of patent 14 years

(Cl. D34—15)

FIG. 1 is an isometric view of a starting signal for road race sets showing my new design thereof;

FIG. 2 is a right side elevational view thereof;

FIG. 3 is a top plan view thereof;

FIG. 4 is a front elevational view thereof; and

FIG. 5 is a rear elevational view thereof.

I claim the ornamental design for a starting signal for road race sets, substantially as shown.
